[57] CLAIM

The ornamental design for a squeegee, as shown.

DESCRIPTION

FIG. 1 is a front elevational view of the squeegee of the present invention;

FIG. 2 is a back elevational view of the squeegee of FIG. 1;
FIG. 3 is a left side elevational view of the squeegee of FIG. 1;

FIG. 4 is a right side elevational view of the squeegee of FIG. 1;

FIG. 5 is a top plan view of the squeegee of FIG. 1; and,
FIG. 6 is a bottom plan view of the squeegee of FIG. 1.

The broken line showing of the handle in FIGS. 3 and 4 is for illustrative purposes only and forms no part of the claimed design.
